UNITED STATES PATENT OFFICE.

GEORGE FREDRICK WATKINS, OF CHICAGO, ILLINOIS.

ANTIRADIATING FURNACE-GATE.

SPECIFICATION forming part of Letters Patent No. 766,301, dated August 2, 1904.

Application filed November 5, 1903. Serial No. 179,965. (No model.)

To all whom it may concern:

Be it known that I, GEORGE FREDRICK WATKINS, a citizen of the United States, residing at Chicago, in the county of Cook and State 5 of Illinois, have invented a new and useful Antiradiating Furnace-Gate, of which the following is a specification.

My invention relates to improvements in furnace-gates, whereby the rays of heat penetrating a furnace-gate and the absorbing of such heat-rays by the coal in the furnace-hopper is reduced to a minimum and liability of ignition of the coal in the furnace-hopper and damage from smoke into the furnace or boiler 15 room prevented. I attain these objects by the apparatus illustrated in the accompanying drawings, in which—

Figure 1 shows a front view of my antiradiating furnace-gate adapted to a furnace provided with revolving grate-bars. Fig. 2 shows a transverse view of the same. Fig. 3 also shows a transverse view with parts left off to clearly show the parts illustrated in the said view.

Similar letters refer to similar parts throughout the several views.

The sides A and the revolving grate-bars *g* constitute a part of a furnace mechanism to which my antiradiating furnace-gate B is shown adapted thereto so as to cover the furnace-mouth, and the said antiradiating furnace-gate is of a box form and has an inner and central web *b*, situated longitudinally and reaching from one end to within a short distance of the opposite end of the said antiradiating furnace-gate.

The antiradiating furnace-gate B is suspended and held in position to cover the mouth of the furnace by the suspended screw-rods 40 *c* taking into the nuts *c'*, confined in pockets formed upon the said gate B, and the suspended screw-rods *c* are rigidly attached to the gear-wheels *c''*, that are supported from the brackets *r*, secured to the sides A, constituting a part of the furnace mechanism. The gear-wheels *c''*, rigidly attached to the upper ends of the screw-rods *c*, mesh with similar gear-wheels *c*, situated upon and firmly at-

tached to the horizontal shaft *f*, taking into the pillows *a* and provided with a hand-wheel 50 *j*. The antiradiating furnace-gate is also provided with an inlet-pipe *p* for water and an outlet-pipe *p'*, also for water, and each of the said pipes *p* *p'* is provided with expansion-boxes *d* *d'*, that the said pipes take into to admit of any required adjustment of the said furnace-gate to the face of the revolving grate-bars *g*. The said furnace-gate is also provided with a thermometer *t* that the furnace-man can regulate the supply of water passing 60 through the interior of the gate with reference to its temperature that the water does not become too high in temperature or pressure. The pop or blow-off valve *i* prevents the pressure of the water passing through the 65 said furnace-gate B from becoming greater than the amount set for the said valve to blow off at and insures safety in the use of the antiradiating furnace-gate B.

Having described the several parts of my 70 antiradiating furnace-gate, the objects avoided and objects attained are more fully described as follows: Coal being supplied to the hopper H is confined between the sides A, the incline sheet or plate *h*, and the antiradiating 75 furnace-gate B, and these several parts virtually form the coal-hopper H of the furnace, and when an ordinary metal plate or frame backed with brick forms the gate to the furnace-mouth the heat from the furnace radiating from such metal plate or frame backed with brick is often sufficient to ignite the coal in the hopper H, causing unnecessary smoke in the furnace or boiler room and always emitting an unnecessary amount of radiant 80 heat into the stoker's quarters.

The antiradiating furnace-gate B being of a box form and internally supplied with cold water constantly flowing through the said furnace-gate is a means whereby the heat 90 taken up by the said antiradiating-gate B is rapidly removed and carried away by the flow of water passing internally through the said gate, whereby the coal in the hopper H is prevented from overheating and igniting in the 95 said hopper, insuring more satisfactory re-

sults in the use of the coal and more comfortable conditions for the stoker to perform his work or duty.

What I claim as my invention, and desire to secure by Letters Patent, is—

1. An antiradiating furnace-gate B, of a box form provided with a horizontal division-web b, of the screw-rods c, taking into nuts c', and suspended from gear-wheels c'', meshing with the gear-wheels e, attached to the shaft f, supported from the pillows a, of the frame A, substantially as shown and described.
2. An antiradiating furnace-gate B, of a box form, provided with screw-rods c, taking

into nuts c', confined in pockets formed upon the gate B, and suspended from the gear-wheels c'', supported from brackets r, of the said gear-wheels, meshing with the gear-wheels e, attached to the shaft f, supported from the pillows a, of the frame A, substantially as shown and described.

In testimony whereof I have signed my name to this specification in the presence of two subscribing witnesses.

GEORGE FREDRICK WATKINS.
